FLEXIBLE APRON LOOP DRIER

Joseph Roberts, Philadelphia, Pa., assignor to
Proctor & Schwartz, Incorporated, Philadelphia, Pa., a corporation of Pennsylvania.

Application March 25, 1936. Serial No. 438,877

9 Claims. (Cl. 34—12)

This invention relates to apparatus for drying or otherwise treating plastic materials such as paints, pigments, chemicals, etc.

The apparatus in general is similar to that shown and described in the co-pending application of Alpheus O. Hurxthal, Serial No. 370,862, filed June 13, 1929, in which the material to be dried is pressed into the openings of an endless foraminous conveyer apron, provided, at spaced intervals, with girts which extend beyond the longitudinal side edges of the conveyer, in order that the apron may be formed into loops suspended by the protruding ends of the girts resting on relatively slow moving supports which are disposed adjacent the opposite side edges of the apron.

The protruding ends of the girts also provide means by which the conveyer is advanced through the apparatus, a pair of drive chains being respectively disposed adjacent the oppositely disposed side edges of the conveyer, at one place only in the apparatus. These drive chains are provided with lugs which engage the said projecting ends of the girts and travel with the conveyer through but a relatively small portion of the apparatus, only two or three of the girts being engaged by the drive lugs at any one time, therefore, the whole of the driving force required for advancing the entire conveyer through the apparatus is of necessity taken by the relatively small number of girts engaged by the drive chain lugs. This condition has a tendency to place that portion of the conveyer which follows the last engaged girt under extremely high tension, which, when additional resistance is presented to the progress of the conveyer, causes the conveyer to break.

The object of the present invention is to relieve the tension of the conveyer proper, by providing drive chains which are substantially the same length as the conveyer belt, and which are permanently and respectively connected to each end of each girt throughout the entire length of the conveyer, the drive chains being formed in loops substantially the same as the loops formed in the conveyer when that looped portion of the conveyer is suspended in the loops on the slow moving supports above noted.

50 Referring to the accompanying drawings:

Fig. 1 is a diagrammatic longitudinal sectional elevation of a drying apparatus showing my invention as applied thereto;

Fig. 2 is a diagrammatic transverse sectional elevation taken on the line 2—2, Fig. 1;

Fig. 3 is a sectional plan view taken on the line 3—3, Fig. 1;

Fig. 4 is an enlarged sectional elevation showing the relation existing between the drive chains and the conveyer apron when the apron is hanging in loops on the moving supports; and

Fig. 5 is a fragmentary sectional elevation taken on the line 5—5, Fig. 4.

In the drawings, a drier casing is diagrammatically illustrated at 1. Rotatably mounted within the casing 1 are transversely extending shafts 2, 3, 4, 5 and 6. On the opposite ends of each of these shafts are secured sprockets 7, 8, 9, 10 and 11 respectively, around which pass drive chains 12, 12 of a foraminous material-carrying apron 15 which, together with the side chains 12, 12, comprises a series of apron sections 20, 20, each of which comprises a pair of girts 16, 16 having trunnions 17, 17 at their respective opposite ends which are rotatably mounted in suitable bearings 18, 18 carried by the drive chains 12, 12 respectively.

As shown in the drawings, there is a girt 16 secured to each end of each flexible foraminous apron section 20, the body portion of which is similar in construction to the foraminous conveyer shown and described in the pending application of Alpheus O. Hurxthal, Serial No. 305,589, filed September 13, 1928.

The sum of the lengths of the apron sections 20 of the material-carrying apron 15 is substantially equal to the total length of each of the side chains 12, 12 so that the side chains 12, 12 and the apron section 20 carried therebetween will move through the apparatus in the same manner as a one piece endless flat conveyer, the back end 21 of each apron section 20 occupying a position immediately adjacent the forward edge 22 of the next successive apron section 20.

The empty conveyer 15 is adapted to be carried around and over the top of a roller 26 mounted on the shaft 2, while the side chains 12, 12 of the conveyer are passing around the sprockets 7, 7 on the said shaft. The apron 15 then passes 100 in a substantially horizontal plane through a suitable pasting mechanism 25 where the material 2, in a plastic state, is pressed into the openings 24 (see Fig. 5) of the apron sections 20.

If desired, the space between the adjacent ends of adjoining sections may be closed by a plate 19 (see Figs. 4 and 5) pivotally connected to the girts 16 of the section 20 in axial alignment with the trunnions 17 of said girts to prevent the plastic material from entering the space be-

tween the adjacent edges of the two girts as they pass through the pasting mechanism 25.

After the material to be treated has been pressed into the conveyer sections the conveyer passes under and partly around a roller 27 mounted on the shaft 3 while the side chains 12, 12 pass around the sprockets 8, 8 on the said shaft.

The conveyer apron 15, after passing under the roller 27, assumes a substantially vertical plane, each section 20 thereof being supported therein by its girts 16, 16 which in turn are supported and carried by the side chains 12, 12, disposed between vertically disposed guides 28, 28 located in one end of the casing 1. The girts 16 raise the sections through this vertical plane and at the top of the casing 1 carry the sections around and over a roller 23 mounted on the shaft 4 between the sprockets 9, 9 thereon, the side chains 12 passing over the top of the sprocket wheels 9, 9 carried by the shaft 4.

After the leading girt 16 of an apron section 20 passes over the top of the sprockets 9, 9, the outer ends of the trunnions 17, 17 of the girt, which extends beyond the side chains 12, 12, are engaged by inclined guides 29, 29 disposed at the opposite sides of the casing 1, and as the chains 12, 12 are fed forward by the sprockets 9, 9 the girt 16 is permitted to slide down the inclined guides 29, 29 until the outer ends of the trunnions 17 of the girt come to rest on slowly moving supports 30, 30 disposed respectively at opposite sides of the casing 1.

These slowly moving supports 30, 30 in the present instances comprise sprocket chains which pass around sprockets 31, 31 mounted on a transversely extending shaft 32 located at one end of the casing 1 and around sprockets 33, 33 mounted on a second transversely extending shaft 34 disposed at the opposite end of the casing 1.

The movable supports 30, 30 are adapted to be driven by any suitable means at any predetermined rate of speed relative to the speed of travel of the conveyer 15, in passing through the pasting mechanism 25, the relation of the speed of travel of the conveyer 15 and that of the supports 30, 30 determining the relative spacing of the leading girts 16 of the respective apron sections 20, 20 on the moving supports 30, 30.

After the leading girt 16 of one section 20 is disposed on the movable supports 30, 30 the body portion of the conveyer section 20 and the portion of each side chain 12 between the leading girt 16 and the trailing girt 16 at the rear end of the section are formed into loops 35 and 35^a respectively, as clearly shown in Figs. 1 and 3, the plate 19 disposed between the trailing end of one section and the lead end of the next successive section of the conveyer apron 20 determining the relative positions to be assumed between the adjacent pairs of girts 16, 16 on the movable supports 30, 30.

The support chains 30, as shown in Figs. 4 and 5 are provided with rollers 36 which ride on suitable rails 37, carried by the framework of the casing 1.

As the supports 30, 30 advance the looped conveyer 15 and drive chains 12, 12 through the casing 1, and as the leading section 20 on the movable supports 30, 30 approaches the delivery end of the drying chamber 1 the side chains 12, 12 of the conveyer, passing around the sprockets 10, 10 on the shaft 5, draw the said side chains 12, 12 out of the leading loops 35^a, the apron section 20 passing around and over

a roller 40 mounted on the shaft 5 between the sprockets 10, 10 thereon, is likewise drawn out of the loop 35 which is located in the lead on the movable supports 30, 30.

During the passage of the conveyer sections 20 through the casing 1 the material carried by the said sections is subjected to a drying or other suitable processing and is made ready to be removed from the conveyer 15.

After passing over the roller 40 the apron 15 is fed downwardly between a pair of substantially vertically disposed guides 41 and 42, it being understood that there is a pair of guides 41, 42 adjacent each of the opposite sides of the casing 1, and these guides are so positioned with respect to the conveyer 15 that they engage the various conveyer sections 20 inward of and immediately adjacent the longitudinal side edges thereof, so that as the conveyer section 20 moves downwardly in the casing 1 it will be supported in a substantially vertical plane.

While in this substantially vertical position between the guides 41 and 42 the conveyer section 20 is subjected to a tapping or beating operation effected by a suitable beater 45 which is adapted to be intermittently moved away from the conveyer section and then permitted to strike the said conveyer section in order to beat the material out of the openings of the conveyer section, the material falling into a suitable hopper 46 provided with a feed screw 47 which is adapted to remove the material from the casing 1.

Adjacent the lower end of the casing the side chains 12, 12 pass around the sprockets 11, 11 on the shaft 6 carrying the girt 16 around a roller 48 mounted on the shaft 6 intermediate the sprockets 11, 11, the body of the apron section 20 attached to the girt 16 passing around the said roller and onto a horizontally disposed partition 50 in the casing 1.

As the side chains 12, 12 move horizontally the conveyer sections 20 are drawn by their leading girts 16 along the partition or floor 50 and return to the feed end of the apparatus, at which the shaft 2 and roller 7 are located.

From the above description, it will be obvious that, by providing side or drive chains which are substantially the same length as the conveyer apron, and by providing girts at spaced intervals along the conveyer apron, and by securing the ends of the girts to the side chains, I am able to apply the driving thrust to the conveyer at a number of points along its length, thereby distributing the said driving thrust in such a manner that no excessive strain is placed on any part of the conveyer apron.

The shafts 2, 3, 4, 5 and 6 are adapted to be driven in any suitable manner in synchronism with each other to properly apply power to the side chains 12, 12 whereby the conveyer apron 15 is advanced through the apparatus, is properly formed into suitable loops for the purpose of treating the material carried by the apron and is properly drawn out of the loops so that the treated material may be readily removed from the apron.

I claim:

1. In an apparatus for treating plastic materials, a foraminous conveyer comprising a body portion of predetermined thickness sufficient to retain material in openings extending perpendicular to and inwardly from at least one of the opposite faces of the said body portion of the conveyer, said body portion comprising a plurality of festooned sections, side chains disposed adjacent to and disconnected from the opposite side edges

- respectively of said body portion, and grits disposed in and confined to the plane of said body portion and permanently connected to the opposite ends respectively of each section and to said 5 side chains. 2. In an apparatus for treating plastic materials, a foraminous conveyer comprising a body portion of predetermined thickness sufficient to retain material in openings extending perpendicular to and inwardly from at least one of the opposite faces of the said body portion of the conveyer, said body portion comprising a plurality of festoon sections, side chains disposed adjacent to and disconnected from the opposite side edges 10 respectively of said body portion, girts disposed in and confined to the plane of said body portion and permanently connected to the opposite ends respectively of each section and to said side chains, and means for driving the side chains to 15 advance the conveyer through the apparatus as a unit. 3. In an apparatus for treating plastic materials, a foraminous conveyer comprising a body portion of predetermined thickness sufficient to retain material in openings extending perpendicular to and inwardly from at least one of the opposite faces of the said body portion of the conveyer, side chains disposed adjacent to and disconnected from the opposite side edges respectively 20 of said body portion, girts disposed in and confined to the plane of said body portion and permanently connected to the said body portion at opposite ends of sections thereof and to said side chains, means for driving the side chains to advance the conveyer through one portion of the apparatus as a unit, and means for forming side chains and the body portion of the conveyer into loops of substantially equal lengths in another portion of the apparatus. 4. In an apparatus for treating plastic materials, a foraminous conveyer comprising a pair of laterally spaced side chains, a plurality of individual body sections arranged in lineal end to end relation between and disconnected from said 25 side chains along their opposite side edges respectively, each body section being of a predetermined thickness sufficient to retain material in openings formed therein perpendicular to the plane thereof, girts extending transversely of the conveyer in and confined to the plane of said body sections and permanently secured to the opposite ends respectively of each section, and means for permanently securing the opposite ends of each girt to the side chains respectively. 5. In an apparatus for treating plastic materials, a foraminous conveyer comprising a pair of laterally spaced side chains, a plurality of individual body sections arranged in lineal end to end relation between and disconnected from said side chains along their opposite side edges respectively, each body section being of a predetermined thickness sufficient to retain material in openings formed therein perpendicular to the plane thereof, girts extending transversely of the conveyer in and confined to the plane of said body sections and permanently secured to the opposite ends respectively of each section, a trunnion on each of the opposite ends of each girt, a bearing for each trunnion and permanently secured to the side chains, and means extending across the space between each pair of adjacent relatively spaced girts and pivoted to said girts in axial alignment with the trunnions thereof to complete the continuity of said body 115 portion of the conveyer. 6. In an apparatus for treating plastic materials, a foraminous conveyer comprising a pair of laterally spaced side chains, a continuous body portion comprising a plurality of individual body sections arranged in lineal end to end longitudinally spaced relation between and disconnected from said side chains along their opposite side edges respectively, each body section being of a predetermined thickness sufficient to retain material in openings formed therein perpendicular to the plane thereof, grits extending transversely of the conveyer in and confined to the plane of said body sections and permanently secured to the opposite ends respectively of each section, means for permanently securing the opposite ends of each girt to the side chains respectively, and means extending across the spaces between the adjacent ends of successive body sections to complete the continuity of the body portion of the conveyer. 7. In an apparatus for treating plastic materials, a foraminous conveyer comprising a pair of laterally spaced side chains, a continuous body portion comprising a plurality of individual body sections arranged in lineal end to end longitudinally spaced relation between and disconnected from said side chains along their opposite side edges respectively, each body section being of a predetermined thickness sufficient to retain material in openings formed therein perpendicular to the plane thereof, grits extending transversely of the conveyer in and confined to the plane of said body sections and permanently secured to the opposite ends respectively of each section, a trunnion on each of the opposite ends of each girt, a bearing for each trunnion and permanently secured to the side chains, and means extending across the space between each pair of adjacent relatively spaced girts and pivoted to said girts in axial alignment with the trunnions thereof to complete the continuity of said body 115 portion of the conveyer. 8. In an apparatus for treating plastic materials, a foraminous conveyer comprising a plurality of body sections, a girt located at and secured to each end of each section, a pair of side chains disposed respectively adjacent the side edges of the conveyer, each of said side chains having a length substantially equal to the sum of the lengths of the plurality of sections of which the conveyer body is composed, means for securing each girt to each of the respective side chains, and a closure plate disposed between adjacent positioned girts of adjoining sections of the conveyer apron. 9. In an apparatus for treating plastic materials, a foraminous conveyer comprising a plurality of body sections, a girt located at and secured to each end of each section, a trunnion extending from each end of each girt, a pair of side chains disposed respectively adjacent the side edges of the conveyer, each of said side chains having a length substantially equal to the sum of the lengths of the plurality of sections of which the conveyer body is composed, bearings on the respective side chains for receiving the girt trunnions, and a closure plate disposed between adjacently positioned girts of adjoining sections of the conveyer apron, said plate being pivoted to said girts in axial alignment with the trunnions thereof. 6. In an apparatus for treating plastic materials, a foraminous conveyer comprising a pair of laterally spaced side chains, a continuous body portion comprising a plurality of individual body sections arranged in lineal end to end longitudinally spaced relation between and disconnected from said side chains along their opposite side edges respectively, each body section being of a predetermined thickness sufficient to retain material in openings formed therein perpendicular to the plane thereof, grits extending transversely of the conveyer in and confined to the plane of said body sections and permanently secured to the opposite ends respectively of each section, means for permanently securing the opposite ends of each girt to the side chains respectively, and means extending across the spaces between the adjacent ends of successive body sections to complete the continuity of the body portion of the conveyer.

JOSEPH ROBERTS.
